Primary Examiner—A. Hugo Word*Assistant Examiner*—Celia A. Murphy*Attorney, Agent, or Firm*—Leonard Tachner[57] **CLAIM**

The ornamental design for a storage case for compact discs, as shown and described.

DESCRIPTION

FIG. 1 is an isometric view of a storage case for compact discs in a closed configuration and showing our new design;

FIG. 2 is a left side elevational view thereof, the right side being a mirror image;

FIG. 3 is a rear elevational view thereof;

FIG. 4 is a front elevational view thereof;

FIG. 5 is a top plan view thereof; and,

FIG. 6 is an isometric view of our new design shown in its opened configuration.

FIG. 1

FIG. 2

FIG. 3

FIG. 4

FIG. 5

FIG. 6
